UNITED STATES PATENT OFFICE.

ANDREW GABRYSZEK, OF DETROIT, MICHIGAN.

COMBINATION WASHING-BRUSH.

1,358,195.

Specification of Letters Patent. Patented Nov. 9, 1920.

Application filed October 15, 1919. Serial No. 330,748.

To all whom it may concern:

Be it known that I, ANDREW GABRYSZEK, a citizen of Poland, residing at Detroit, county of Wayne, and State of Michigan, have invented certain new and useful Improvements in Combination Washing-Brushes, of which the following is a specification.

The invention relates to improvements in cleaning brushes, particularly brushes for washing floors, windows and the like.

The principal object of the invention is to provide a brush which is adapted to be supplied with water from a suitable source, particularly adapted to be attached to the spigot of the water supply for a house.

Another object of the invention is to provide a brush that is so constructed that it can be automatically set closer or farther away from the object to be cleaned.

While the essential and characteristic features of the invention are susceptible of modification, still the preferred embodiment of the invention is illustrated in the accompanying drawing, in which;—

Figure 1 is a side view of the device attached to a spigot, and

Fig. 2 is a cross section through the brush head.

The brush casing 10 is provided with a nipple 11 at its upper end into which the

lower end of a tubular handle 12 is screwed, the upper end of which is adapted to be connected by a flexible hose 13 or the like to a spigot 14 of the water supply pipe. 35 The brush holder 15 is secured to the flanged bottom 16 of the casing 10, and is provided with a plurality of apertures,—17, 17, through which the water from the spigot is supplied to the bristles 18, 18 of the 40 brush. The quantity of the supply of water is regulated in the well known manner. Rubber bodies 19—19, heart-shaped in cross-section are attached to arms 20, 20 at the sides of the casing in such a manner that 45 they can be rotated to vary the pressure of the brush on the surface to be cleaned.

What I claim is:—

A cleaning brush of the character described comprising in combination, a flanged 50 casing, a perforate back attached to the flanges of said casing, rubber bodies, heart shaped in cross-section, secured to said casing adjacent the brushing surface and adapted to be rotated to vary the pressure 55 of the brush on the surface to be cleaned, means for supplying water to said brush and means for controlling said water supply.

In testimony whereof I have affixed my signature.

ANDREW GABRYSZEK.
